US00D606549S

(12) **United States Design Patent**
He

(10) **Patent No.:** **US D606,549 S**
(45) **Date of Patent:** **** Dec. 22, 2009**

(54) **STORAGE DEVICE**

(75) Inventor: **Shu-Gang He**, Guangdong (CN)

(73) Assignee: **FIH (Hong Kong) Limited**, Kowloon (HK)

(**) Term: **14 Years**

(21) Appl. No.: **29/326,241**

(22) Filed: **Oct. 15, 2008**

(30) **Foreign Application Priority Data**

Sep. 19, 2008 (CN) 2008 3 0301512

(51) **LOC (9) Cl.** **14-99**

(52) **U.S. Cl.** **D14/480.7**

(58) **Field of Classification Search** D14/300-302, D14/314, 348-358, 411, 432, 433, 435.1, D14/436, 480.1-480.7, 484.1, 496, 125, 137, D14/155, 167, 168, 203.1-203.8, 240, 242, D14/299; D13/107, 108, 149, 184; 312/223.1, 312/223.2; 369/34.01, 36.01, 272.1; 360/97.01, 360/132, 133, 135; 361/752; 710/300, 301; 439/131, 135-147

See application file for complete search history.

(57) **CLAIM**

The ornamental design for a storage device, as shown and described.

DESCRIPTION

FIG. 1 is a perspective view of a storage device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view; and,

FIG. 8 is another perspective view thereof, wherein the USB connector is shown in an extended position.

The broken lines shown in the drawings are included for the purpose of illustrating unclaimed portions of the storage device and form no part of the claimed design.

1 Claim, 8 Drawing Sheets
